CLAW BAR

Bruce J. Barker, Richmond, Ind.

Application May 26, 1941, Serial No. 395,159

6 Claims. (Cl. 254—25)

This invention relates to improvements in claw bars and it consists of the matters hereinafter described and more particularly pointed out in the appended claims.

The claw bars with which the present invention is more especially concerned are of the kind used in pulling or withdrawing spikes from the ties of a railroad track. The conventional type of claw bar, of which many are in use for the purpose mentioned, consists of a lever-like bar having a foot that includes a bifurcated part at one end providing the spike head engaging claw, and a heel at the other end about which the bar is fulcrumed in pulling a spike. As heretofore made, the conventional claw bar is open to certain objections, which the present invention seeks to overcome.

For instance, in the use of the conventional bar, occasionally the head of a spike is broken off and flies into space with great force. Should the flying spike head strike the workman using the bar, serious injuries often result. Also, when the spike head breaks off under the bearing down pressure on the bar, the workman's hand suffers painful injuries by forcefully hitting adjacent ties, rails or the larger stones in the ballast. Again, in the use of the conventional claw bar, the toe is sometimes driven into position with respect to the spike operated upon, by the use of a track maul. This not only requires the temporary service of another workman, but involves certain dangers to both workmen, such as flying chips of steel and the like. Furthermore, in the use of the conventional claw bar when removing spikes, the spikes are often bent out of their original straight condition so as to be incapable of reuse. Therefore, they are scrapped and become an economic loss.

One of the objects of the present invention is to provide a simple means for converting a conventional type claw bar into one capable of use for its intended purpose, with safety for the workmen against personal injury and which at the same time will not bend the spike to an extent making it unfit for reuse.

Another object of the invention is to provide simple and efficient means adapted to be attached to the toe end of the foot of a conventional type claw bar, for not only restraining a spike head from flying into space, should it break off from the shank of the spike, but also to provide a second claw for engagement with the spike in removing the same from a tie without swinging the bar about its fulcrum through the arc neces-

sary in the use of the conventional type claw bar, which causes a bending of the spike.

Again, it is an object of the invention to provide simple and efficient means which may be readily attached to a conventional type claw bar, without weakening the same, for the purpose of providing a guard that prevents engagement of the workman's hand with parts of the track in a manner often resulting in painful injury to the hand.

The above mentioned objects of the invention as well as others, together with the advantages thereof, will more fully appear as the specification proceeds.

15. In the drawing:

Fig. 1 is a view in side elevation of a conventional type claw bar, of which many are in service today and which, according to the present invention, may be readily made into a safer and more efficient claw bar, at a very low cost.

20. Fig. 2 is a top plan view of the conventional type claw bar appearing in Fig. 1.

Fig. 3 is a view in side elevation of the claw bar appearing in Fig. 1, after it has been modified or made into a safer and more efficient bar by the use of my invention.

25. Fig. 4 is a transverse vertical sectional view, on an enlarged scale, through the toe end of the bar shown in Fig. 3 as taken on the line 4—4 of Fig. 3.

30. Fig. 5 is another transverse vertical sectional view, on the scale of Fig. 4, through the fulcrum heel portion of the bar shown in Fig. 3 as taken on the line 5—5 of Fig. 3.

35. Fig. 6 is a perspective view of a certain shield forming a part of my invention and adapted for attachment to the claw or toe end of the foot of the conventional type claw bar of Fig. 1.

40. Fig. 7 is a bottom view of the shield appearing in Fig. 6.

Fig. 8 is a perspective view of a certain fulcrum block forming a part of the invention and which is adapted for attachment to the heel of the foot of the conventional type claw bar of

45. Fig. 1.

Fig. 9 is a fragmentary perspective view of a certain hand guard forming a part of my invention and which is adapted for attachment to a part of the conventional type claw bar of Fig. 1 as will later appear.

50. The conventional type claw bar, such as shown in Fig. 1, comprises a lever-like bar 10 usually about five feet long and enlarged at one end to provide a foot 11 and formed at the other end with a point 12. The foot has a somewhat

55

rounded bottom 13 which terminates at one end at the toe 14 of the foot and merges at its other end into a fulcrum heel 15. The toe end of the foot is widened out laterally and has a central recess 16 and laterally spaced prongs 17 that define the claw of the bar. Such a bar is usually made as a forging and is properly hardened throughout.

In the use of such a bar, the spaced prongs 17 of the toe are engaged under the head of the spike, at which time at least a part of the neck of the spike (not shown) is disposed in the recess. By bearing down on the other end of the bar, the foot 11 fulcrums about the heel 15 and lifts or withdraws the spike. In order to dispose the prongs under the head of certain spikes, it is often the custom to drive the prongs under the spike head. This is accomplished by another workman striking the back of the heel with a track maul while the first workman holds the bar.

In drawing or pulling spikes, with a conventional type claw bar, the spike sometimes breaks off at the neck and as there is nothing on the top side of the foot to confine the head, it flies into space with great force. If the flying head strikes the workmen, a serious injury often results. When a spike breaks in the fashion mentioned, the other end of the bar, released from its lift resistance, slams downwardly. It usually carries the operator's hands therewith to so forcefully engage the fingers of the hands against the road bed or adjacent track parts as to bruise, mash and sometimes break the fingers.

In order to convert or make the conventional type claw bar into one wherein the workman is fully guarded against the possible injuries above mentioned, I provide certain parts which may be attached to conventional type claw bars, whether new ones or those in service, and such parts are shown in perspective in Figs. 6, 8, and 9 respectively.

In Fig. 6 is shown a shield element that includes a hollow body 18 that is open at the front 19 and at the bottom 20 and is closed at the top and at the rear end. In the front end of the top is a longitudinal recess 21 and in the bottom edge of the body is a plurality of bevelled portions 22 for welding purposes. The shield above mentioned has a plan contour to fit on the front end of the top surface of the toe 14. When said shield is positioned on the toe, the recess 21 is disposed above the recess 16 in the toe and the open front is substantially flush with the front extremity of the prongs 17-17. Strips of welding 23 (see Fig. 4) are then laid in the bevelled recesses 22 to attach the shield to the foot. The shield thus provides a chamber above the toe of sufficient height and area amply to receive the head of a railroad spike. It is pointed out that by welding the shield to the foot as mentioned, no such welding heat is applied to the end portions of the prongs 17 of the toe, as will withdraw the hardness therefrom. Such welding is sufficient for the purpose because in the use of the shield part of the bar for pulling, the welding is placed under compression.

In Fig. 8, I have illustrated a heel "lift" element 24 of a somewhat right angular or L shape to include a body portion 24 and tapering end 70 portions 26 and 27, the former being longer than the latter. This element has a top surface 28 of a contour to fit upon the heel 15 of the bar, the extension 26 fitting a part of the bottom of the foot and the extension 27 fitting the curve

where the heel joins the bottom of the bar 10. The longitudinal corners of the top surface of the lift element are bevelled as at 29. When the lift element 24 is in place upon the foot and heel 5 parts of the bar, a line of welding 30 (see Fig. 5) is laid in each groove defined by the bevelled edges 29 and associated parts of the claw bar.

In Fig. 9 I have illustrated a fragment of a hand guard member that includes a bar portion 10 31 having a somewhat upwardly extended arm 32 at each end. Each arm terminates in a semi-cylindrical bar engaging portion 33 of such cross sectional shape as to partially surround that part of the bottom of the bar 10 with which it is engaged. When positioned upon the bar, the edges of the portions 33 are welded thereto as at 34.

In the use of the bar embodying the parts described and best shown in Figs. 3, 6, 8 and 9, the prongs 17 of the toe 14 are engaged under 20 a spike head as before, and this disposes the spike head in the chamber as provided by the shield element. By bearing down upon the opposite end of the bar, it fulcrums about the heel lift and the spike is initially and partially withdrawn 25 from the tie to that extent which will not bend the same. Should the spike head snap off, it cannot fly into space because it is confined by the shield. Also, as the opposite end of the bar swings down rapidly toward adjacent parts of 30 the road bed, the guard 31 will engage the same so that the workman's fingers cannot forcefully engage therewith.

When the spike has been initially withdrawn, 35 the bar is removed from the spike and reinserted with the neck of the partially drawn spike disposed in the recess 21 of the shield and with parts of the head of the spike engaged on the top of the shield at each side of the recess. This provides a second bite for the bar which is then 40 swung downwardly as before about the heel lift 24 as a fulcrum to impart the final lift to the spike which withdraws it from the tie.

In this respect, it is pointed out that it is only 45 in the initial part of the pulling of the spike that said spike is placed under such tension as will cause the head to snap off. The final lifting movement of the spike is comparatively easy and no such tension develops in the spike as will cause the same to break. Thus, in the two steps 50 of pulling the spike, it is not subjected to a bending strain that will prohibit its reuse.

It is apparent from the above that by means 55 of the invention, I am enabled to convert a conventional type claw bar, many of which are in service, into one which is not only positively safe in use for the workman but which leaves the withdrawn spikes in a condition fit for reuse.

The present invention also contemplates the manufacture of this type of device initially by 60 making the conventional type bar and the shield part separately and then securing them together in the manner previously described. In this way, the main part can be readily forged and the whole device made at much lower cost than would be possible were the entire structure made as a forging.

While in describing the invention, I have referred in detail to the form and arrangement of the parts involved, as well as to one way in which said parts are attached to a conventional claw bar, the same is to be considered only in the illustrative sense so that I do not wish to be limited thereto except as may be specifically set forth in the appended claims.

I claim as my invention:

1. As an article of manufacture, a shield adapted for attachment to the end of the foot of a claw bar having a recess therein, said shield comprising a hollow member open at one end and at its bottom and having side and end walls and a top wall portion, there being a recess in the front end of said top wall portion.

2. As an article of manufacture, a shield adapted for attachment to the end of the foot of a claw bar having a recess therein, said shield comprising a hollow member open at one end and at its bottom and having side and end walls and a top wall, the bottom edges of said side and end walls having longitudinally spaced apart welding recesses therein.

3. As an article of manufacture, a shield adapted for attachment to the end of the foot of a claw bar having a recess therein, said shield comprising a hollow member open at one end and at its bottom and having side and end walls and a top wall, there being a recess in the front end of said top wall and the bottom edges of said side and end walls having longitudinally spaced welding recesses therein.

4. A claw bar embodying therein a foot having a toe with a claw forming recess therein at one end and a fulcrum heel at the other end, a hollow shield member open at one end and at the bottom and having side and end walls, the bottom edge of which is engaged upon and welded to the top surface of said toe, with its open end facing the

free end of the toe and providing an open front spike head receiving recess above the recess in said toe, there being a recess in that part of the open end of said shield member and disposed above and substantially in line with the recess in the toe.

5. A claw bar embodying therein a foot having a toe with a claw forming recess therein at one end and a fulcrum heel at the other end, a hollow shield member open at one end and at the bottom and having side and end walls, the bottom edge of which is engaged upon the top surface of said toe, with its open end facing the free end of the toe and providing an open front spike head receiving recess above the recess in said toe, said bottom edge having longitudinally spaced recesses therein, and welding disposed in said recesses for securing said shield to said surface of the toe.

6. A claw bar embodying therein a foot having a toe with a claw forming recess therein at one end and a fulcrum heel at the other end, a hollow shield member open at one end and at the bottom and having side and end walls and a top wall portion, the bottom edge of said side and end walls being engaged upon and welded at longitudinally spaced points to the top surface of the toe with its open end facing the free end of the toe and providing an open spike head receiving recess above said toe, said top wall portion of the shield having a recess at its front end disposed above the recess in said toe.

BRUCE J. BARKER.
